CLAIM

The ornamental design for a telephone, substantially as shown and described.

DESCRIPTION

FIG. 1 is a front, top and right side perspective view of a telephone showing our new design;

FIG. 2 is a front, top and left side perspective view thereof with the handset removed from the telephone base;

FIG. 3 is a front elevational view thereof;

FIG. 4 is a rear elevational view thereof;

FIG. 5 is a top plan view thereof;

FIG. 6 is a right side elevational view thereof;

FIG. 7 is a left side elevational view thereof;

FIG. 8 is a bottom plan view thereof;

FIG. 9 is a front, top, and right side perspective view of a second embodiment thereof;

FIG. 10 is a front, top and left side perspective view thereof with the handset removed from the telephone base;

FIG. 11 is a front elevational view thereof;

FIG. 12 is a rear elevational view thereof;

FIG. 13 is a top plan view thereof;

FIG. 14 is a right side elevational view thereof;

FIG. 15 is a left side elevational view thereof; and

FIG. 16 is a bottom plan view thereof.
